SASH

Charles E. Lyon, Decatur, Ill., assignor to G. S. Lyon & Sons Lumber & Mfg. Co., Decatur, Ill., a corporation of Illinois

Application May 9, 1932, Serial No. 610,110

4 Claims. (Cl. 20—40)

This invention relates to sash for forming window openings or the like, and with regard to certain more specific features, to wooden sash of this class.

5 Among the several objects of the invention may be noted the provision of a sash construction adapted to be installed into a wall without the use of a separate frame therefor; the provision of a sash of the class described in which 60 substantial strength of its members are distributed substantially equally over the entire area of the opening; the provision of a sash of the class described having increased area of glass in relation to the size of opening in which the sash 65 is installed; the provision of a sash of this class adapted to cover a larger area with more safety and convenience of installation of the sash and auxiliary members such as movable window screen and the like; and the provision of a sash of this 70 class which forms a better break against air leakage through the opening in which it is installed. Other objects will be in part obvious and in part pointed out hereinafter.

The invention accordingly comprises the elements and combinations of elements, features of construction, and arrangements of parts which will be exemplified in the structures hereinafter described, and the scope of the application of which will be indicated in the following claims.

30 In the accompanying drawings, in which are illustrated several of various possible embodiments of the invention,

Fig. 1 is a perspective view of one form of sash viewed from the screen side thereof, certain portions of the screening being removed and showing an inner movable window;

Fig. 2 is a vertical section taken on line 2—2 of Fig. 1;

Fig. 3 is a horizontal section taken on line 40 3—3 of Fig. 1;

Fig. 4 is a view similar to Fig. 1 showing a modified form of the invention;

Fig. 5 is a view similar to Fig. 4 showing another modification;

45 Fig. 6 is a horizontal section taken on line 6—6 of Fig. 5;

Fig. 7 is a vertical section taken on line 7—7 of Fig. 5; and,

Fig. 8 is a fragmentary, horizontal section 50 taken on line 8—8 of Fig. 1, and showing a wind break.

Similar reference characters indicate corresponding parts throughout the several views of the drawings.

55 Heretofore, wood sash have been made with

heavy peripheral frames, the full strength of the sash in resisting wall and wind load having been in these frames. The frames have, because of their bulk, blocked the passage of a substantial amount of light through the opening covered 60 by the respective windows. Lattice work has been built into these heavy frames, but this lattice has not been designed to take either wind or wall loads, the same being only strong enough to supply and glaze in the glass and involving an undesirable flexibility.

As a result of the above disadvantages, wooden sash have not been extensively used. For openings of considerable area, steel frames have been resorted to.

70 With the present invention, it is possible to enclose openings with wood sash which heretofore could not be closed thereby. Wood sash does not deteriorate as rapidly as steel sash, particularly in locations where smoke and other 75 chemical impurities of the air cause acid attacks, or where moisture is present. Moisture, both plain and acidulated, more quickly attacks metal sash than it does wooden ones. Furthermore, the wood sash may be flame and/or fireproofed 80 for fire protection. It then has the advantage of reducing fire hazard without functioning as a positive bar against escape by occupants of a burning building, as does steel. The wood, although resisting fire can in emergency be manually broken out to permit escape, whereas steel cannot. Wood sash also retains more building 85 heat than does steel sash.

Referring now more particularly to Figs. 1 and 2, there is illustrated at numeral 1 a peripheral 90 framework of wood whose cross section is of the order of one by three inches, although this figure is not to be taken as limiting. The primary feature in view of what follows is that it may be made thinner so as to present less obstructions 95 to entry of light, when compared with the ordinary wooden sash.

Vertically arranged at intervals between the sideward members of the frame 1 are a plurality of studs 3 forming vertical, rectangular openings 100 5. Each vertical, rectangular opening 5 is divided into a series of smaller openings 7 by means of relatively small lateral supports 9 which are not as deep nor as strong as the studs 3. Suitable grooves 11 are formed in the cross supports 9 105 and the studs 3 for the purpose of seating and glazing in panes of glass or the like 13.

If it be found desirable to place within the latticed sash thus far described a window, then suitable sections of the studs 3 are omitted and 110

headers 15 used for outlining (with a pair of the adjacent studs 5) a window opening 17 within which is hinged a window 19. The window may be of any desired class, preferably wood, the type 5 shown in Figs. 1 and 2 being suitable. Grooves 21 in the frame formed by the two sideward studs 3 and headers 15 serve to seat the window and hinges 23 serve to permit opening of the same.

Furthermore, the frame 17 carries rearwardly 10 grooves 25 for receiving a movable screen 27, said screen being hinged by hinges 29.

It is to be understood that the lowermost one of the frame members 1 may comprise a sill S as shown in Fig. 2.

15 Reference to Fig. 3 shows that the lateral thickness of the frame members 1 and the studs 3 is comparable, the frame members 1, in fact, being somewhat thinner than the stud members. The result of this structure is that great rigidity is 20 obtained both as in resisting load applied to the frame from the top and against wind loads. As may be seen from the drawings, the studs form rectangular panels within the integral side frame, which are broken into smaller areas by the lateral members. However, this is not done at the 25 expense of any glass opening and hence the sash, while having all of the advantages and excellent appearance of wood, is comparable in window open effect to the less advantageous steel sash.

30 The lateral glass-holding members 9 are and may be small because the lateral loading is unimportant and the weight of glass per lateral member is negligible.

In Fig. 4 is shown a form of the invention similar to that shown in Fig. 1, except that there 35 are used no headers interiorly of the lattice or cellular structure, no interior window being used within the sash proper. Similar references indicate parts corresponding to those shown in Figs. 40 1 to 3.

In this form of sash (having no swinging window) certain elements of the structure are more clearly emphasized, such as the vertical rectangular spaces 5 broken up into smaller spaces by 45 means of the light cross pieces 9. It will be noted in this connection that adjacent vertical members 5 and/or side members 1, taken with the lighter cross pieces 9 serve to define a ladder arrangement in which the legs thereof serve to provide 50 ample strength but in which the cross pieces are not unnecessarily large.

Viewed in another light, the sash comprises a grid, the edges of which are not any larger than the grid members running in a predetermined 55 direction, and in which the grid members which run crosswise of said predetermined direction are relatively smaller.

In Fig. 5 is shown a form of the invention which is similar to that shown in Fig. 4, except that the 60 frame member 1 (which has characteristics the same as those of the frame member referred to in connection with Figs. 1 to 4) has the ladder-like, lattice-work arranged horizontally, instead of vertically. That is to say, the strong studding 65 31 is parallel to the horizontal edges of the frame 1, rather than to one of the sideward verticals. In this case, the studs 31 are joined by lighter, vertical members 33 for glass placement purposes (see also Fig. 7). This form of the invention 70 causes the studs 31 to support wind loads primarily and is for application where no great vertical load is to be applied from the outside of the frame. It is also useful where endwise loading occurs. As shown, the panels 5 are horizontally arranged.

It will be noted that in the figures of the drawings, the frame 1, with the exception of the sill S is provided with peripheral grooving 35, the purpose of which is to receive a detachable strip 37 serving wind breaking purposes. 80 This strip is held within the groove 35 by means of suitable screws 39 (Fig. 8). The strip 37 is placed within a recess 41 of the ordinary or masonry wall or the like 43 which surrounds the opening. It may also be applied to the sill S, if desired. 85

If it be desired to remove the sash at any time in order to repair it or replace it, the screws 39 may be loosened and the strip 37 pushed further into the recess 41, thus permitting insertion of a new sash member. The displaced strip 37 is shown in dotted lines in Fig. 8. When the new sash is put into place, this may be retrieved in any one of various ways, such as by temporarily using a longer screw. Other 90 methods will suggest themselves to various users. 95

The strip 37 serves as a wind brake by providing a labyrinth, when taken in connection with the wall 43, so that direct air leakage is prevented.

It will be seen that the above invention results in the advantages already enumerated and many others. Among these are the following:

The sash is designed to be installed in a wall without the use of a separate frame, the sash itself providing the requisite strength for taking 105 wall loads or the like. The sash may be installed in any one of the various types of walls used such as brick, masonry, wood stud wall, and wood stud walls with brick veneer.

The sash is positively rigid, practically air 110 tight, removable, and eliminates the customary additional frame. It also lends itself easily to standardization of manufacture, because each unit supplies its proportion of strength. That is, it is not necessary to increase the size of 115 wood members for larger openings. It provides a maximum area of glass in relation to the size of opening. Also, sub-sections of the sash may be used for movable windows, screens and the like. 120

The sash is also designed to withstand exceptional pressure against its surface, making use of much larger areas of sash than were heretofore considered practicable.

In view of the above, it will be seen that the 125 several objects of the invention are achieved and other advantageous results attained.

As many changes could be made in carrying out the above constructions without departing from the scope of the invention, it is intended that all matter contained in the accompanying drawings shall be interpreted as illustrative and not in a limiting sense.

I claim:

1. A wooden sash comprising a frame adapted to be placed within a wall opening, labyrinth means extending from said frame and into said wall, and fasteners for holding said labyrinth means to the frame, said fasteners being adapted to be manipulated without damaging the frame, 135 to permit of freeing of said labyrinth means. 140

2. A wooden sash comprising a frame adapted to be placed within a wall opening, labyrinth means extending from said frame and into said wall, and fasteners for holding said labyrinth means to the frame, said fasteners being adapted to be manipulated without damaging the frame to permit of freeing of said labyrinth means 145 whereby the frame is released to permit its removal from said opening. 150

3. A wooden sash comprising a frame adapted to be placed within a wall opening, labyrinth forming means extending from said frame and into said wall, and fasteners for holding said labyrinth means to the frame, said fasteners being adapted to be manipulated without damaging the frame to permit of freeing of said labyrinth means, said frame being provided with a peripheral recess for receiving said labyrinth means.
- 5 4. A wooden sash comprising a frame adapted to be placed within a wall opening, labyrinth
- means extending from said frame and into said wall, and fasteners for holding said labyrinth means to the frame, said fasteners being adapted to be manipulated without damaging the frame to permit of freeing of said labyrinth means, 80 said frame being provided with a peripheral recess for receiving said labyrinth means, said labyrinth means comprising a tongue in said peripheral groove.
